UNITED STATES PATENT OFFICE.

ARTHUR L. ROBERTS, OF JACKSON, TENNESSEE, ASSIGNOR TO PIGGLY WIGGLY CORPORATION, OF MEMPHIS, TENNESSEE, A CORPORATION OF DELAWARE.

TURNSTILE.

Application filed August 11, 1925. Serial No. 49,620.

My said invention relates to a turnstile which finds its most important use in self-serving stores of the Piggly Wiggly type but may obviously be used in other situations either in the form hereinafter described or in other forms. It is an object of the invention to provide a device of this character which will turn freely in one direction but will be locked against movement in the contrary direction.

10 A further object of the invention is to provide a device of this character in which the locking means shall be concealed.

Another object of the invention is to provide a device of this character in which the various connecting parts, etc. shall be concealed so as to present substantially a plain smooth surface of wood or other material to the observer.

20 Referring to the accompanying drawings which are made a part hereof and on which similar reference characters indicate similar parts,

Figure 1 is a plan of my device,
25 Figure 2, a vertical section partly in elevation,

Figure 3, a horizontal section through the locking means, and

30 Figure 4, a detail of the locking means with the concealing parts omitted.

In the drawings reference character 10 indicates a post, the top only being shown, which post carries a pivot in the form of a wood screw 11. A circular or annular block 12 is secured to the top of the post by means of screws 13 and this block is mounted so as to have its outer surface concentric with the screw 11 and preferably with the outer surface of the post. The block is indicated as having a hollow center but this is not essential.

40 At one side the block has slots 14 formed therein these slots extending circumferentially of the block for a limited distance and growing shallower toward their outer ends as clearly shown in Fig. 3. In the present embodiment of the invention balls 15 are shown in the slots, these balls being forced toward the ends of the slots by means of 45 coil springs 16 bearing at one end against the balls and at the other being formed to clasp pins 17 which are secured in any suitable manner to the block 12. As here shown the slots 14 are of sufficient length to permit the springs to be turned in either direc-

tion so that the balls may be located either to the right or left of the pins 17.

A head 18 is mounted for rotation about the screw 11 as an axis, this head having arms 19 here shown as spaced at intervals of approximately 90° thereabout though this arrangement may be varied at will. The head is provided with a cap 20 secured thereto by screws 21 and this cap is cored out at its under side to receive the head of the screw 60 11 which is concealed by the cap. Obviously the shallow recess indicated in the head 18 under the head of the screw may be of sufficient depth to receive the screw head while the cap may consist of a flat block of 65 wood over the recess in the head and other changes will occur to those skilled in the art.

70 An annular outer shell 22 is secured to the head by screws 23 extending through a horizontal flange 24 integral with the outer shell 22 and said shell extends down approximately to the top of the post 10. The shell surrounds the block 12 and has its inner surface closely adjacent to the outer surface of the block. Preferably a space is left in the horizontal flange 24 extending to the hollow space in the block 12 though this is not essential. Preferably also the head of the screw 11 is spaced from the upper face of the head 18 to permit slight relative up and 75 down movement.

80 The operation of the device is believed to be obvious from the above description in connection with the drawings. It will be understood that by turning the springs through an arc of 180° and moving the balls 15 from one side of the pin to the other the turnstile may be arranged to rotate either to the right or to the left, it being, as above stated, unidirectional in its operation and being locked 85 in either instance against rotation in the reverse direction.

90 It will be obvious to those skilled in the art that various changes may be made in my device without departing from the spirit 100 of the invention and therefore I do not limit myself to what is described in the specification and shown in the drawings but only as indicated in the appended claims.

95 Having thus fully described my said invention what I claim is new and desire to secure by Letters Patent, is:

105 1. A turnstile comprising a fixed post, a rotary head thereon, arms on the head, one or more rollers located between adjacent pe-

ipheral surfaces of the post and the head said surfaces being provided with recesses of varying depth circumferentially of the turnstile, and a resilient means to force such 5 rollers circumferentially of the turnstile into position for locking the head against rotation in one direction, substantially as set forth.

2. A turnstile comprising a fixed post, a 10 rotary head thereon, arms on the head, a screw passing through the head axially into the post, a cap over the head of said screw and means for locking the head against reverse rotation at any position at which it 15 may be stopped, substantially as set forth.

3. A turnstile comprising a fixed post, a rotary head thereon, arms on the head, a screw passing through the head axially into the post, a cap over the head of said screw 20 and spring-pressed rollers for locking the head against movement in one direction, substantially as set forth.

4. A turnstile comprising a fixed post, a circular block fixed to the upper end of the 25 post in coaxial relation thereto, a head having a flange surrounding said block, arms on the head, and spring-pressed rollers

adapted to wedge between the head and the block for locking the head against rotation in one direction, substantially as set forth. 30

5. A turnstile comprising a fixed post, a circular block fixed to the upper end of the post in coaxial relation thereto, a head having a flange surrounding said block, arms 35 on the head, and means between the head and the block for locking the head selectively against rotation in either direction, substantially as set forth.

6. A turnstile comprising a fixed post, a circular block fixed to the upper end of the post in coaxial relation thereto, a head having a flange surrounding said block, and a flange overlying the same, a block secured to the head by screws extending up through the last-named flange, radial arms on said block, a screw extending through said block 40 axially of the post, and a cap covering the head of the last-named screw, substantially as set forth.

In witness whereof, I have hereunto set 50 my hand at Jackson, Tennessee, this 6th day of August, A. D. nineteen hundred and twenty-five.

ARTHUR L. ROBERTS.
